UNITED STATES PATENT OFFICE.

ROBERT W. HARPER, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

Application filed December 24, 1923. Serial No. 682,416.

To all whom it may concern:

Be it known that I, ROBERT W. HARPER, a citizen of the United States of America, residing at East Orange, in the county of 5 Essex and State of New Jersey, have invented certain new and useful Improvements in Telephone Systems, of which the following is a full, clear, concise, and exact description.

10 This invention relates to telephone systems and particularly to systems employing automatic switching apparatus for setting up connections.

The object of the invention is an improvement 15 in automatic telephone systems of small capacity whereby the manner of establishment of connections is simplified and the efficiency of the system in general is increased.

20 According to one feature of the invention there are provided a plurality of relay connecting devices for interconnecting calling and called lines, together with two separate sets of counting relays responsive to 25 successive series of impulses for selectively closing the operating circuits of said relay connecting devices.

Another feature relates to a controlling mechanism consisting of a series of counting 30 relays wherein the first relay of the series operates and releases either when an accidental impulse is to be absorbed or when the first selective impulse is immediately followed by succeeding impulses. In case 35 the first selective impulse is followed after an interval by a single impulse said relay remains operated to effect the desired circuit connection.

The drawings disclose a representation 40 of a preferred means of carrying out the invention. The several figures when arranged in the manner shown in Fig. 11 form a complete circuit diagram.

Fig. 1 shows a number of subscribers' 45 lines arranged in groups. In conjunction with these lines are shown two groups of multi-contact relays with cooperating links. Connected to certain of these relays is shown one of a number of incoming trunks 50 by means of which calls may be extended from the central office to any station. In this figure are also shown two multi-contact connecting devices, each of which is associated with a group of the first mentioned

multi-contact relays for controlling the 55 operation thereof.

Fig. 2 shows one of a number of central office trunks with associated controlling apparatus by means of which a subscriber may obtain connection with a central office. In 60 this figure is also shown an attendant's line together with a number of keys to be used by the attendant, as well as a number of lamps for signaling the attendant under certain conditions.

Fig. 3 shows the attendant's register sender 65 consisting of a number of counting relays whose operation is controlled by the attendant's dial for purpose of selecting a set of the multi-contact relays shown in 70 Fig. 1. Fig. 3 also shows certain controlling equipment.

Fig. 4 shows a plurality of central office 75 trunks, one of which is shown terminating in the contacts of a set of multi-contact relays. Arranged to cooperate with these contacts are a plurality of links. The subscribers' lines are connected to the contacts of another group of multi-contact relays. In this figure is also shown trunk controlling 80 apparatus for controlling the operation of the several groups of multi-contact relays.

Fig. 5 shows common apparatus for supplying ringing current and busy tone, as well 85 as a buzzer circuit for giving an audible signal to the attendant.

Fig. 6 shows the attendant's line circuit 90 with circuit controlling and signaling apparatus.

Fig. 7 shows groups of multi-contact 95 relays, one of these groups of relays acting as a line connector and the other group acting as line finders. Terminating in certain contacts of these relays are shown a number of intermediate links. Arranged to cooperate with these intermediate links are other sets of horizontal links. The horizontal links appearing in the line finder relays will be designated as primary links, while those appearing in the line connectors will be designated, secondary links. Fig. 7 also shows controlling equipment and part of an allotter mechanism.

Fig. 8 shows control apparatus which is 100 individual to each of the intermediate links.

Fig. 9 shows schematically other groups 105 of finder and connector relays with associ-

ated primary, secondary and intermediate links. Fig. 9 also shows besides the line and cut-off relays, a group starting circuit for allowing but one calling line to be connected with an intermediate link at a time. There is also shown an emergency starting circuit and a portion of the allotter mechanism.

Fig. 10 shows a register sender which is associated with an intermediate link for registering the designations of called lines and controlling the operation of the connector relays.

From an examination of the several figures it will be seen that the subscribers' lines are arranged in groups, two of such groups being shown. Each group of lines has associated with it a number of multi-contact relays, as relays 110, 410, 710, 715, etc. Each line of a group has an appearance in separate sets of contacts in each of these multi-contact relays. In Fig. 1 is shown schematically by means of the dotted rectangle 104, a second set of multi-contact relays similar to relays 110, 111, 112, etc., and also an incoming trunk 121 similar to trunk 120. The dotted rectangle represents a second set of multi-contact relays similar to relays 410, 411, 412, etc., and an outgoing trunk 421 which is similar to trunk 420. The dotted rectangle 900 shows schematically a second line connector mechanism similar to that shown at 700 in Fig. 7, while rectangle 901 represents a second line finder mechanism similar to that shown at 701 (Fig. 7).

General description.

When a calling subscriber removes the receiver for the purpose of conversing with another local subscriber, the operation of the line relay causes a particular group relay as 905 to operate and to lock in series with the common relay 906. This prevents a subscriber whose line is in another group causing interference by initiating a call before the first calling line has been connected with an intermediate link through the line finder relays. If the intermediate link 907 is busy, an allotter relay 909 associated therewith, is operated and a circuit will be closed to operate a connecting device 703, thus causing the operation of multi-contact relay 715 which is individual to the group of lines in which the calling line is located. A relay as 708 which corresponds to the units digit of the calling line is next operated. The calling line is thus connected by means of a primary link as 712 with an intermediate link 720.

The calling subscriber next dials the tens digit of the wanted line thus operating and releasing relay 801 a corresponding number of times. Provision is made for absorbing a preliminary impulse by means of relays

1001 and 1002 should the calling subscriber inadvertently dial a tens digit of one. The numbers of the subscribers' lines are so arranged that all tens digits are greater than 1. If the tens digit is greater than 5, however, transfer relay 1003 operates and allows the same register relays to be used for recording tens digits greater than 5 as are used for recording tens digits less than 5. When the tens digit is recorded, a circuit is closed to operate the proper one of the multi-contact relays as 710 which corresponds to the tens digit as recorded on the register 1000. The calling subscriber next dials the units digit of the called line. If this digit is 3 or less, a relay as 1004 is operated. If it is greater than 3, the transfer relay 1005 operates, thus allowing three register relays to be used for recording the units digits 1 to 5. The subscribers' numbers are so grouped that there is no units digit greater than 5. The recording of the units digit on register 1010 causes the operation of the proper multi-contact relay as 725. The calling line is then connected by means of a primary link 711, an intermediate link 720 and a secondary link 727 with the called subscriber's line, ringing current having been applied to the line by the ringing mechanism 500.

Should the called line be busy, relay 802 is operated and busy tone is transmitted from the tone source 550 back to the calling subscriber.

When a subscriber desires to talk to the attendant the operation is similar to that already described as far as the point where the subscriber is ready to dial. In this case the circuits are so arranged that the digit 0, when dialed, causes the operation of a relay as 803 which connects the calling line by means of a primary and intermediate link with the attendant's line 601, causing a lamp 602 to light, thus signaling the attendant. The attendant thereupon operates a key 603 which places a talking set 605 in communication with the calling subscriber.

When a subscriber dials a special code, in this case 11, for the purpose of obtaining connection with the central office, the operation is similar to that described in connection with a local call as far as the point where the impulses are recorded on registers 1000 and 1010. In this case a trunk relay 804 operates and in turn causes the operation of a multi-contact relay 410 which corresponds to the tens digit of the calling line and also operates another multi-contact relay 412 which corresponds to the units digit of the calling line. The operation of relay 804 opens the circuit of slow release relay 1006 which supplies holding ground for the finder relays 704 and 715. When relay 1006 operates, therefore, the finder relays release, thus disconnecting the inter-

mediate link 720 from the calling subscriber's line. The calling subscriber's line is now connected directly through contacts of relays 410 and 412 with an outgoing central office trunk as 420. The subscriber may proceed to dial the central office number, in the case of a mechanical office, or give the number verbally in the case of a manual office.

10 In the case of restricted service with regard to a local subscriber calling a central office, a key 910 individual to the subscriber's line is operated, thus moving the ground for operating the trunk connecting relays 410 and 412 thereby preventing the subscriber from obtaining connection with the central office.

On calls incoming from the central office, as soon as the central office operator applies 20 ringing current to an incoming trunk as shown in Fig. 2, a line lamp 201 lights for the purpose of signaling the attendant who answers by operating a key 212. If the incoming call is for a station, the attendant 25 receives the number from the central office operator and throws a station's key 203 causing her talking set to be disconnected from the central office end of the trunk and transferred to the local end by means of the 30 operation of relay 204. Meanwhile, a bridge is placed across the trunk to hold the connecting apparatus at the central office. The attendant next dials the designation of the wanted station which is recorded on the 35 register sender shown in Fig. 3 consisting of a tens register 300 and a units register 301. When the record has been established, the proper multi-contact relays as 110 and 113 are operated. The former corresponding 40 to the tens digit of the required station as recorded on register 300, while the latter corresponds to the units digit as recorded on the register 301. When relay 113 operates, the attendant's sender (Fig. 3) is 45 released. Busy tone and ringing current are applied to the line in the same manner as for a local call. When the attendant releases the listening key 202 and the station's key 203, the called subscriber's line is connected directly with the central office trunk.

Should the called line be busy when the attendant connects thereto she may break in on the connection by operating key 205. The release of this key will cause the incoming trunk to wait on the busy line and ring it when it becomes idle. The attendant is provided with a release key 206 which, when operated, allows the transfer of an incoming call from one station to another.

50 A disconnect key is provided by means of which the attendant can give a disconnect signal to the central office when a station cannot be connected with. As soon as the attendant answers an incoming call, lamp

208 lights and remains lighted until the 65 local subscriber answers.

The attendant is also provided with a line circuit 610, by means of which she can originate calls to the central office or to any local subscriber. 70

Detailed description of local call.

The description of how a local connection is completed will now be given. For this purpose, assume that the subscriber of line 75 101 desires to talk with subscriber of line 102 whose number is "33". When the calling subscriber removes his receiver from the switchhook, line relay 904, Fig. 9, operates from battery through its winding, left inner 80 armature and back contact of relay 911, ring conductor of the calling line, through the substation apparatus, back over the tip side of the calling line to ground at the outer armature and back contact of relay 911. 85 The operation of relay 904 connects ground at its right armature and front contact through the right hand winding of group relay 905 to battery at the back contact of the common relay 906. Relay 905 closes a 90 locking circuit for itself from the above traced ground through its left winding and the left inner armature and front contact to battery through the winding of relay 906 95 which operates. The operation of relay 906 removes the battery for energizing other group relays similar to relay 905. Thus, if a subscriber whose line is in another group now initiates a call, his line will not be connected to a line finder until the previous 100 calling line has first been connected. If two subscribers, whose lines are in different groups initiate calls simultaneously, the subscriber whose line is in the lower numbered group will have his line extended first, since the operation of the lower numbered group relay opens at its left inner armature and front contact the locking circuit for all 105 succeeding similar relays.

At this point, it will be noticed that each 110 intermediate link as link 907, Fig. 9, has associated with it two allotter relays as 909 and 912. Similarly, intermediate link 720, Fig. 7, has associated with it allotter relays 705 and 706. Once an intermediate link has been used the allotter relays associated therewith remain locked until the last intermediate link has functioned. The operation of the allotter relays associated with the last intermediate trunk opens the locking circuit for all preceding allotter relays which release, thus permitting a new cycle of allotting of intermediate links to begin.

Under certain circumstances, it may be desirable to have each link test idle as soon as it functions in the completion of a call. In this case, key 707, is operated thereby removing the locking ground from all the 120 125

allotter relays and permitting the same link to be used a number of times in succession.

Returning now to the point where the group relay 905 was operated and assuming that the intermediate link 907 has just been taken for use then relays 909 and 912 associated therewith, will remain locked in series to ground at key 707. The operation of group relay 905 therefore closes a circuit from ground at its right inner armature and front contact starting conductor 915, outer armature and back contact of relay 913, armature and back contact of relay 914, left armature and front contact of relay 909, conductor 950, left armature and back contact of relay 705, to battery through the winding of relay 703 which operates. Relay 703 closes a locking circuit for itself from battery through its winding locking armature and contact, conductor 952, winding of relay 914 to ground as above traced. Relay 914 does not operate at this time since its winding is shunted by ground through the left armature and front contact of relay 909. The operation of relay 703 closes a circuit for energizing the particular multi-contact finder relay as 708 which corresponds to the units digit of the calling line, and also a particular group finder relay as 715 which corresponds to the group in which the calling line is located. The circuits for the purpose are as follows: From battery through the winding of relay 708, armature and contact of relay 703, conductor 750, left armature and front contact of relay 904 to ground at the left outer armature and front contact of relay 905. Relay 715 operates from battery through its winding, contacts of relay 703, conductor 951 to ground at the right outer armature and front contact of relay 905.

The operation of finder relays 708 and 715, connects the calling line 101 through primary link 712 with the intermediate link 720. Relay 801, thereupon operates from battery through its winding, tip conductor of the link 720, contacts of relay 708 and relay 715 to the tip side of the calling line through the calling subscriber's set, back over the ring side of the calling line, contacts of relays 715 and 708, ring side of link 720 to ground through the winding of relay 801. The operation of relay 801 causes the operation of the holding relay 1006 from battery through its winding, conductor 1050, left outer armature and back contact of relay 804, left armature and contact of relay 801, conductor 850 to ground through the winding of low resistance relay 551, which operates to start the tone mechanism 550.

Relay 1006, in operating, performs the following functions:

1. Connects ground through its left armature and contact, conductor 1051, resistances 722 and 723 in parallel to the ar-

tures and locking contacts of relays 708 and 715, thus providing substitute holding circuits for the finder relays which are independent of relay 703.

2. Connects ground through its right armature and contact, conductor 1052, to battery through the left winding of relay 705. Relay 705 locks from battery through its right hand winding, winding of relay 706, right armature and contact of relay 705 to ground at key 707. The operation of relay 705 transfers the starting circuit to the next link.

3. Connects ground through its right armature and contact to conductor 1053, sleeve conductor of intermediate link 720, contacts of relays 708 and 715, sleeve conductor of the calling line to battery through the winding of cut-off relay 911. Relay 911 operates in this circuit and renders the line 101 busy to other calling lines.

When relay 705 operated it removed the shunt from the winding of relay 914 which now operates and prevents this same calling line becoming associated with another intermediate link through the left armature and front contact of relay 705. The operation of cut-off relay 911 causes the release of line relay 904 and group relay 905. The release of relay 905 breaks the holding circuit for relays 914 and 703 which now release and render the starting circuit and allotter mechanism available for use in connection with another calling line.

The calling subscriber now dials the tens digit of the wanted line. Relay 801, Fig. 8, upon the transmitting of the first impulse will release. The release of relay 801 removes the short circuit from around the winding of relay 805 which operates from battery, left armature and contact of relay 808, retardation coil 806, winding of relay 805, right armature and contact of relay 808 to grounded conductor 1053. The operation of relay 805 connects the battery at the left armature and contact of relay 808 through the armature and contact of relay 805, winding of slow-release relay 807, conductor 852, left armature and back contact of relay 1007, left inner armatures and back contacts of relays 1008, 1009, 1011, 1012, in series, and thence through the winding of relay 1013 to the grounded conductor 1053. Relays 1013 and 807 operate in this circuit. After the transmission of the first impulse relay 801 again operates, thus causing the release of relay 805. Relay 805 on releasing removes the short circuit from around the winding of relay 1012 which now operates in series with relay 1013. The operation of relay 1013 closes a circuit for operating relay 1002 from grounded conductor 1053, winding of relay 1002, right inner armature and contact of relay 1001, left armature and contact of relay 1013,

130

right armature and back contact of relay 1017, normal contacts of relay 1003, conductor 1054, to battery at the left armature and contact of relay 808. At the termination of the first impulse, relay 1001 operates in series with relay 1002 in a manner similar to that described in connection with relay 1012. Relay 1002 closes a circuit from ground at the left outer armature and contact of relay 1003, right armature and contact of relay 1002, winding of relay 1018, conductor 1054, to battery at the armature and contact of relay 808. Relay 1018 closes a locking circuit for itself in series with the winding of relay 1007 to grounded conductor 1053. Relay 1007 does not operate in this circuit since its winding is shunted by the above traced ground and by ground at its right inner armature and back contact. The transmission of the next impulse in the tens train causes relay 805 to again operate and connect battery through its armature and contact, winding of relay 807, conductor 852, left armature and back contact of relay 1007, left inner armature and back contacts of relays 1008, 1009, 1011 in series, left inner armature and front contact of relay 1012 to ground through the winding of relay 1014 which operates and locks in series with relay 1011 in the manner already described. The operation of relays 1011 and 1014 causes the release of relays 1012, 1013, 1001 and 1002. In a similar manner the transmission of the third and last impulse of the tens series causes the operation of relays 1009 and 1015 and the release of relays 1011 and 1014. In the comparatively long interval following the train of tens impulses, relay 807 releases. The release of relay 807 removes ground from the conductor 865 thus allowing relay 1007 to operate and lock in series with relay 1018. The operation of relay 1007 connects ground through its right outer armature and contact, right armature and back contact of relay 1003, right inner armature and front contact of relay 1009, conductor 1055, winding of relay 709 to battery. Group connecting relay 709 locks in a circuit from battery through its winding, armature and locking contact, resistance 716 to the grounded sleeve conductor of intermediate link 720. At this point it will be observed that the locking circuit of counting relays 1017 and 1019 is different from the locking circuit of other counting relays, the circuit comprising the left normal contacts of relay 1003. This is for the purpose of recording a tens digit greater than 5. In such a case the transmission of the sixth impulse causes counting relay 1013 to operate from grounded conductor 1053, winding of relay 1013, left inner armature and back contact of relays 1012, 1011, 1009, 1008 in series, left armature and back contact of relay 1007, conductor 852, to battery through the winding of relay 807. As soon as relay 805 releases at the end of the sixth impulse, relay 1012 operates in series with relay 1013 as before described. As soon as relay 1012 operates a circuit is closed to operate a group transfer relay 1003 from grounded conductor 1053, winding of relay 1003, left inner armature and front contact of relay 1019, left outer armature and front contact of relay 1012, conductor 1054 to battery at the armature of relay 808. Transfer relay 1003 locks from grounded conductor 1053, through its winding, left inner armature and front contact, conductor 1054 to the above traced battery. The operation of relay 1003 therefore causes the release of counting relays 1017 and 1019. The ground for operating the connector relays shown in Fig. 7 is now transferred to the right armature and front contact of relay 1003 and the outer right armature and front contact of the operated counting relay. Thus by means of transfer relay 1003 tens digits greater than 5 may be recorded on five sets of counting relays and the proper corresponding connector relay energized.

Returning to the point where relay 1018 locked in series with relay 1007, subsequent to the termination of dialing of the tens digit, the calling subscriber next manipulates the dial to transmit the units digit, in this case 3. The release of relay 801 on the first impulse causes the operation of relay 805 as already described and a circuit is closed from battery through the left armature and contact of relay 808, armature and contact of relay 805, winding of relay 807, conductor 852, left armature and front contact of relay 1007, left inner armature and back contacts of relays 1022 and 1004 in series, through the winding of relay 1020 to ground at the right armature and contact of relay 1006. When relay 805 releases on the termination of the first impulse the short circuit is removed from the winding of relay 1004 which now operates in series with relay 1020. In a similar manner the transmission of the second impulse causes the operation of relays 1021 and 1022 and the release of relays 1004 and 1020. Since the number of the called line is assumed to be 33, three units impulses will be sent and relays 1023 and 1024 will operate, causing the release of relays 1021 and 1022. If, however, the units digit had been greater than 3, a units transfer relay 1005 would operate and function in a manner to that already described for group transfer relay 1003.

When the subscriber has finished dialing the units digit, the slow relay 807 releases and connects ground through its right normal contacts, conductor 860, right armature

and contact of relay 1018, resistance 1025, left outer armature and back contact of relay 1005, right armature and contact of relay 1024, conductor 1056 to battery through 5 the winding of units connector relay 717. With group connector relay 709 and units connector relay 717 operated, a circuit is closed to energize the slow operating relay 808 from the grounded conductor 1053, winding 10 of relay 808, conductor 853 to the armature and locking contact of connector relay 717 and thence through the winding of this relay to battery. After an interval when relay 808 operates, battery is removed from 15 its left armature causing the release of counting relays 1009, 1015, 1024, 1023 and also relay 1007 and 1018.

The calling line is now connected by means of primary link 712, intermediate link 720 20 and secondary link 713 with the called subscriber's line and a test thereof is made prior to ringing. It will be noted that when relay 1018 operated subsequent to the dialing of the tens digit, a circuit was closed from battery through the right hand winding of test relay 809, conductor 854, left outer armature and contact of relay 1018 to the grounded conductor 1053. If the called line is busy the sleeve conductor 718 will be grounded 25 in a manner similar to that already described in connection with rendering the calling line 101 busy. Test relay 809 will, therefore, remain locked from battery, through its left winding, normal contacts of relay 802, left 30 inner armature and front contact of relay 809, thence to the grounded sleeve conductor of the called line. Relay 802 will also operate from battery through its winding and 35 normal contacts to the above traced ground and will lock through the left outer armature and contact of relay 809 to the grounded sleeve conductor of intermediate link 720. The operation of relay 802 causes a busy tone to be sent from the tone source 550, 40 conductor 552, conductor 855 right armature and front contact of relay 802, condenser 810, ring conductor of the intermediate link and 45 thence over the calling subscriber's line notifying him that the called line is busy. This 50 busy tone is cut off from the wanted line by relay 812 which operated as soon as relay 809 closed its left outer armature and front contact.

If, however, the called line is idle there 55 will be no ground on the sleeve conductor 718. When relay 1018 releases, test relay 809 will also release. The release of relay 809 will connect ground through its left inner 60 armature and back contact and thence to the sleeve of the conductor of the called line, thus rendering the called line busy to other calling lines. In this case relay 802 will not operate, but relay 812 will remain locked from battery through the winding of relay 65 501, conductor 560, left winding of relay

812, left armature and contact thereof, left outer armature and back contact of relay 802, armature and contact of relay 813 to the grounded sleeve conductor of the link. Relay 501 operates in this circuit and starts 70 the ringing mechanism 500 in the manner to be described hereinafter. This causes ringing current to be induced in the winding 75 502 of the ringing transformer thence over conductor 530, winding of relay 813, right 75 outer armature and back contact of relay 809, right outer armature and front contact of relay 812 to the ring side of the called 80 line, through the called subscriber's ringing apparatus, back over the tip side of the line, right inner armature and front contact of relay 812, right inner armature and back contact of relay 809, conductor 561, thence to ground at the winding 502 of the ringing 85 transformer.

When the called subscriber removes his receiver the resistance of the circuit including relay 813 is reduced. Relay 813 operates and at its armature and back contact opens the locking circuit for relay 812 and ringing 90 start relay 501, the latter cutting off the ringing mechanism. The release of relay 812 extends the tip and ring conductor of the calling line to the tip and ring conductors of the called line. Relay 814 operates and 95 supplies talking current to the called subscriber. The operation of relay 814 places ground on the sleeve conductor of the intermediate link to hold the link and connector relays after the calling subscriber has disconnected. 100

Disconnection.

When the calling subscriber replaces his receiver on the switchbook, relay 801 releases, 105 in turn releasing relay 1006. When relay 1006 releases it opens the holding circuit of finder relays 708 and 715 and cut-off relay 911. However, the remainder of the connection is under control of the called subscriber. 110

When the called subscriber replaces his receiver relay 814 releases opening the holding circuit for connector relays 717 and 709 which release. If the key 707 is operated the release of relay 814 will cause the release of 115 allotter relays 705 and 706, thus rendering intermediate link 720 selectable by another calling line. However, if key 707 is normal, allotter relays 705 and 706 will remain locked and intermediate link 720 will not be selectable until all succeeding links have functioned. 120

Emergency start circuit.

It will be remembered that when the calling subscriber initiated the call, a group relay 905 operated to start the selection of an intermediate link as 720. Let it be assumed that intermediate link 907, Fig. 9, is idle. Therefore, allotter relays 909 and 912 are released. If, however, intermediate link 130

907 is not associated with the calling line within a certain time, the emergency start circuit functions to allot another idle intermediate link and connect the calling line thereto. For this purpose the emergency start circuit begins to function immediately that a group relay as 905 operates. Relay 916 operates from battery at the normal contacts of relay 917, winding of relay 916 to the grounded conductor 915. The operation of relay 916 closes an obvious circuit for relay 917 which is slow to operate. When relay 917 has operated relay 916 starts to release. Relay 917, in operating, closes a circuit from battery through the left winding of relay 913, winding of relay 918, left inner armature and back contact of relay 913, left armature and contact of relay 917 to the grounded conductor 915. Relay 918 operates in this circuit but relay 913 does not. After an interval relay 916 releases, in turn, releasing relay 917. When relay 917 releases a circuit is closed from battery, through the left winding of relay 913, winding of relay 918, right hand winding of relay 913, right armature and contact of relay 918 to the grounded conductor 915. Relay 913 operates in this circuit. Another cycle of operation of relays 916 and 917 occurs. On the second operation of relay 917, relay 913 locks, but relay 918 is shunted and releases. While relay 916 is releasing the second time, a circuit is closed from the grounded conductor 915, left middle armature and front contact of relay 913, left inner armature and back contact of relay 918, left armature and back contact of relay 912 to battery through the right hand winding of relay 909. After an interval slow relay 916 releases and disconnects ground from the left armature of relay 912 which now operates in series with the left winding of relay 909 to ground at key 707. Thus by means of two cycles of operating and releasing of relays 916 and 917, if allotter relays 909 and 912 do not operate normally as described for a local call, the emergency start circuit functions to operate these allotter relays and thus extend start wire 919 to the next link.

Preliminary pulse circuit.

The register mechanisms shown in Figs. 3 and 10 are so arranged that if a comparatively long interval ensues between the first impulse transmitted and subsequent impulses, the first impulse will not be counted. If, however, the first impulse is one of a train of impulses, the preliminary pulse circuit does not function. It will be remembered in connection with the recording of the first impulse on register 1000, preliminary pulse relay 1002 operated in conjunction with counting relays 1012 and 1013. If,

therefore, an interval intervenes between this first impulse and the next succeeding impulse, relay 807 will release and open the holding circuit for counting relays 1012 and 1013 which also release. At the same time the short circuit is removed from the winding of relay 1001 which now operates in series with relay 1002. The operation of relay 1002 prevents the operation of relay 1007 and a consequent shifting to the units register 1010, since relay 1007 is shunted by ground at the left armature of relay 1003. On a subsequent impulse which may be assumed to be the first normal impulse, relays 1012 and 1013 re-operate to record this as the first impulse, subsequent impulses being recorded in the usual manner. This absorption of a preliminary impulse is made use of in dialing the central office code, namely 11, in such a manner that the first pulse is recorded on the preliminary pulse relays 1001 and 1002 and the second impulse is recorded on the relays 1012 and 1013 without operating any relays of the units register 1010. The combination of relays 1001 and 1012 causes the operation of a trunk relay 804 as described later in connection with an outgoing trunk call.

Trunk circuit outgoing calls.

When a local subscriber dials the special code 11 with the purpose of communicating with the central office, the operation is similar to that already described in connection with a local call as far as the point where the number is recorded on the register 1000. In this case, since there is a units digit of 1, the first impulse will cause the operation of relays 1001, 1002, 1012 and 1013. When relay 807 releases after this impulse, counting relays 1012 and 1013 release, but relays 1001 and 1002 remain operated. The subscriber then dials the units digit 1. This causes the re-operation of relays 1012 and 1013. However, when relay 807 releases following the dialing of the units digit, counting relays 1012 and 1013 remain operated from grounded conductor 1053, windings of relays 1013 and 1012 in series, right armature and front contact of relay 1013, right outer armature and front contact of relay 1001, conductor 1054, to battery at the armature of relay 808.

With counting relay 1012 and preliminary pulse relay 1001 operated, a circuit is closed to operate trunk relay 804 from battery at the armature and contact of relay 815, right hand winding of relay 804, conductor 862, left armature and contact of relay 1001, right inner armature and front contact of relay 1012, conductor 860, right normal contacts of relay 807, to the grounded conductor 1053. Relay 804 closes a lock-

ing circuit for itself from grounded conductor 1052, left inner armature, front contact and left winding of relay 804, to battery through the winding of relay 815 which 5 operates and prevents the operation of other trunk relays similar to 804. When relay 804 operated, it opened at its left outer armature and back contact the holding circuit for relay 1006, which is slow to release. 10 Immediately that relay 804 operated, it closed a circuit for the connecting device 405 associated with an idle outgoing trunk. Assuming that the central office trunk 421 is busy, then relay 403 associated therewith is 15 operated and a circuit will be closed to operate relay 405 in the event that trunk 420 is the next idle trunk. The circuit for this purpose is as follows: from battery through the winding of relay 405, left armature and 20 back contact of relay 407, left armature and front contact of relay 406, conductor 751, left outer armature and front contact of relay 804, left armature and contact of relay 801, conductor 850, to ground through the winding of relay 551. The operation of relay 405 closes a circuit for operating a trunk group relay 410 corresponding to the group in which the calling line is located, and also 25 a trunk units relay 408 which corresponds to the units digit of the calling line. The circuit for relay 410 is from battery through its winding, lowermost armature and contact of relay 405, conductor 450, contacts of finder group relay 715, conductor 752, right outer armature and contacts of relay 804, conductor 863 of the intermediate link, contacts of finder relays 708 and 715, to ground 30 at the key 910. In the case of restricted service, there will be no ground at key 910 and the calling subscriber will be unable to obtain connection with the central office. The circuit for operating units relay 408 extends from battery through its winding, uppermost armature and contact of relay 405, conductor 452, armature and contact of relay 708, conductor 753, to the above traced ground. 40

Immediately that relays 408 and 410 operate, the calling line is connected with trunk 420 and relay 415 operates in series with the calling line. Relay 415 closes an obvious circuit for relay 416. Relay 416 in operating connects ground through its left armature and contact in parallel through resistances 413 and 414 to provide locking circuits for the operated trunk units and trunk group relays 408 and 410 respectively. 50

After an interval when slow relay 1006 has released, ground is removed from the conductor 1051, thus causing the release of finder relays 708 and 715. The release of these latter relays disconnects primary link 712 and secondary link 720 from the calling line, causing the release of relay 801, which 60 in turn causes the release of relay 405. The

release of relay 1006 also opens the locking circuits for relays 804 and 815, which are now released for use in associating another calling line with a central office trunk. The line 101 is held busy to other calling lines 76 by ground on the sleeve conductor which is applied when relay 416 operates, thus maintaining cut-off relay 911 energized when finder relays 708 and 715 release. 75

When relay 415 operated subsequent to the connection of line 101 with trunk 420, ground at the outer armature and front contact of relay 415 was placed on the tip side of the trunk, causing the operation of the line relay at the central office and giving a signal to the operator. When the central office operator answers, relay 409 operates since it is bridged across the trunk. Relay 409 closes an obvious circuit for slow-release relay 417. The operation of relay 417 80 closes a circuit from battery through the winding of relay 418, right armature and contact of relay 416, to ground at the left armature and contact of relay 417. Relay 418 in operating, connects the calling line 85 directly with the central office trunk and releases relay 415. At the same time, supervisory relay 419 operates, in turn closing an obvious circuit for relay 423. Relay 423 90 opens the operating circuit of relay 409 and provides a substitute holding circuit for relay 417. When relay 415 released it removed the short circuit from around the winding of relay 407, which now operates to 95 render outgoing trunk 420 busy, and to extend the starting conductor 453 to the next 100 idle link. 100

Should all the central office trunks be busy when the calling subscriber dials the central office code, a circuit will be closed 105 from the grounded starting conductor 751, through the left armatures and front contacts of all relays similar to 407, conductor 451, left hand winding of relay 816, to battery at the right inner armature and front contact of relay 804. A tone will then be transmitted from the tone source 550, conductor 552, conductor 855, left inner armature and front contact of relay 816, condenser 810, and thence to the ring side of the calling line, notifying the calling subscriber 110 of the busy condition. 115

When the calling subscriber replaces the receiver on the switchhook, relay 419 releases, causing the release of relay 423. The remainder of the connection is under the control of the central office operator by means of relay 409 re-operating upon the release of relay 423, thus providing a holding circuit for relay 417 and maintaining the units and group connector relays energized. When the central office operator disconnects, relay 409 releases, in turn releasing relays 417, 418, 416 and the connector relays 408 and 410. Relay 407 also 120 125 130

releases and renders trunk 420 selectable by other calling lines.

Incoming calls.

- 5 When a central office operator plugs in on an incoming trunk, as shown in Fig. 2, relay 209 operates from a source of ground at the central office, (not shown) ring side of the trunk, left middle contacts of key 207, windings of relay 209, right normal contacts of key 233, inner normal contacts of relay 204, tip side of the trunk, right normal contacts of key 207, to battery (not shown) at the central office. Relay 209 10 closes an obvious circuit for slow-release relay 210, which causes the lamp 202 to be lighted as a signal to the attendant. When ringing current is applied to the trunk, relay 213 operates since its left hand winding is bridged across the trunk in series 15 with condenser 214. Relay 213 closes a locking circuit for itself from battery, through its right hand winding, right outer armature and contact of relay 216, left inner armature and contact of relay 213, to ground at the armature of relay 210. Line lamp 201 20 lights from battery through the winding of relay 560, conductor 253, lamp 201, to ground through the left outer armature and front contact of relay 213. Relay 560 operates in this circuit, causing buzzer relay 561 to vibrate, thus giving an audible signal to the attendant. The attendant answers by operating listening key 212, which 25 connects her telephone set across conductors 263 and 264 and thence across the central office trunk through the normal contacts of relay 204. Relays 219, 220 and 221 also operate at this time over obvious circuits. 30 After receiving the number of the desired station, the attendant operates station's key 203 and dials the desired number. Assume that the number of the wanted line is 23. Immediately that the key 212 is thrown, relay 216 operates over an obvious circuit and closes a circuit from the grounded conductor 250, left normal contacts of relay 217, left inner armature and back contact of relay 232, right inner armature and contact of relay 216, to battery through the guard lamp 208 which remains lighted until the called subscriber has answered. The operation of relay 216 also connected retardation coil 218 in parallel with the right hand high resistance winding of relay 209. The operation of relay 216 also opened the locking circuit of relay 213, causing the line lamp 201 to be extinguished. 35 When the attendant operated station's key 203, ground was connected through the right middle contacts of key 212, left contacts of key 203, in parallel circuit to battery through the windings of relays 204 and 217. Relay 204 transfers the talking set from the 40 outgoing end of the trunk to the local end, thereby operating relay 222. Relay 217 closes a circuit from battery through the winding of relay 103, conductor 150, right outer armature, and contact of relay 217, right armature and contact of relay 223, 70 left outer armature and front contact of relay 217, to ground at key 206. Relay 103 operates in this circuit and extends the above traced ground through its lower armature and front contact over conductor 157 75 to battery through the winding of relay 303. The attendant now dials the tens digit of the desired station. The release of relay 222 on the transmission of the first impulse, removes ground at its left armature and 80 contact from the conductor 251, and conductor 351, thus allowing relay 302 to operate from battery at the armature and contact of relay 303, retardation coil 304, winding of relay 302, to grounded conductor 350. 85 This same battery is extended through the right armature and front contact of relay 302, winding of slow-release relay 305, right armature and back contact of relay 306, right outer armatures and back contacts of 90 relays 307, 308, 309 and 310 in series, winding relay 311, to the grounded conductor 350. The operation of relay 311 closes a circuit from grounded conductor 350, winding of preliminary pulse relay 313, right 95 armature and back contact of relay 312, right armature and front contact of relay 311, left armature and back contact of relay 319, left normal contacts of relay 316, conductor 354, to battery at the armature 100 and contact of relay 303. At the termination of the first impulse, ground is again applied to conductor 351, causing the release of relay 302 and the removal of the short circuits from around the windings of relays 105 310 and 312, which now operate. The operation of relay 313 closed a circuit from battery at the armature and contact of relay 303, winding of relay 315, right armature and front contact of relay 313, to 110 ground at the left outer armature and contact of relay 316. Relay 315 locks in series with the winding of relay 306, but relay 306 does not operate since it is shunted by the above traced ground. Since the tens digit 115 of the called line is assumed to be 2, the transmission of the second impulse causes the operation of counting relays 309 and 314 and the release of relays 310, 311, 312 and 313. Following the dialing of the tens digit, relay 305 releases and removes the short circuit from around the winding of relay 306, which now operates in series with relay 315 to the grounded conductor 350. 120 The operation of relay 306 extends the ground at conductor 350 through the left outer armature and front contact of relay 306, right armature and back contact of relay 316, left inner armature and front contact of relay 309, conductor 353, contacts 125 130

of relay 103, to battery through the winding of group connector relay 110. Relay 110 closes a locking circuit for itself from battery through its winding and locking contact, conductor 152, left outer armature and front contact of relay 217, to ground at key 206.

When relay 306 operated, it also transferred the impulsing circuit to the units 10 register 301 and the recording of the units digit is similar to that already described for a local call. In the case assumed relays 317 and 318 remain operated at the end of the units dialing. When relay 305 releases 15 at the termination of the units series, a circuit is closed from battery through the winding of units connector relay 113, contacts of relay 103, conductor 153, left inner armature and front contact of relay 317, left armature and back contact of relay 320, resistance 321, right armature and front contact of relay 315, left normal contacts of relay 305, to the grounded conductor 350. Relay 113 closes a locking circuit from battery 20 through its winding and locking contact, conductor 154, winding of relay 223 left outer armature and front contact of relay 217, to ground at key 206. Relay 223 operates in this circuit and opens the holding circuit for relay 103, which releases. Relay 25 103 causes the release of relays 303, 315, 306 and the operated counting relays. The attendant's sender is thereby released for use in connection with another call.

35 The testing of the called line is accomplished in substantially the same manner as described for a local call. Test relay 224 operated when relay 315 closed its left armature and front contact. If the called line 40 is busy, relay 224 will remain locked through its right hand winding, normal contacts of relay 225, left outer armature and front contact of relay 224, to the grounded sleeve conductor of the busy line. When relay 45 224 closed its left inner armature and front contact relay 226 operated through its right hand winding. At the same time a circuit was closed for relay 225 from battery at the right armature and contact of relay 234, 50 winding of relay 225, left normal contacts of relay 225, to the above traced ground. Relay 225 also locks to ground at key 206 and a busy tone is transmitted to the attendant from a tone source 550, conductor 552, 55 right armature and front contact of relay 225, condenser 235, lower outer armature and front contact of relay 204, left inner contacts of key 212, conductor 264 through the attendant's set, conductor 263, left outer 60 contacts of key 212, lower inner armature and front contact of relay 204, left normal contacts of relay 228, to ground through the left hand winding of relay 222.

65 By means of key 205, the central office can be automatically connected to a busy line

when the line becomes idle. The attendant operates key 205 which extends ground through the right inner armature and front contact of relay 217 to battery through the winding of relay 236. The operation of relay 236 places the attendant's set in communication with the busy line and closes a circuit from battery through the winding of relay 234, upper armature and front contact of relay 236, left outer armature and front contact of relay 224, to the grounded sleeve conductor of the busy line. Relay 234 locks through the left outer armature and front contact of relay 224 to the sleeve of the busy line. This condition exists until the called station becomes idle, at which time ground is removed from the sleeve, releasing relays 234 and 224. As soon as it becomes idle the desired station is therefore rung in the manner hereinafter described and without further action by the attendant.

If the called line is idle, relay 224 will release after the units dialing but relay 226 will remain locked from battery through the winding of relay 501, left hand winding of relay 226, left inner armature and contact thereof, left inner armature and contact of relay 225, right armature and contact of relay 227, left outer armature and front contact of relay 217, to ground at key 206. The operation of relay 501 starts the ringing mechanism 550 and ringing current is transmitted over conductor 502, winding of relay 227, right outer armature and back contact of relay 224, right outer armature and front contact of relay 226, ring side of the trunk, thence over the ring side of the calling line through the subscriber's ringing apparatus, back over the tip side of the calling line, tip side of the trunk, right inner armature and front contact of relay 226, right inner armature and contact of relay 224, conductor 511, to ground at the winding 502 of the ringing transformer. The attendant may now restore her keys. The restoring of key 212 releases relays 204 and 217.

When the called subscriber answers, relay 227 operates, opening the holding circuit of relays 501 and 226, which release. Relay 501 stops the ringing mechanism, and relay 226 connects the called line to the contacts of relay 228, thus operating relay 222. At this time, relay 230 operates from battery through its winding, left inner armature and back contact of relay 217, left armature and contact of relay 223, left outer armature and contact of relay 226, to ground at the left armature of relay 222. Relay 230 closes an obvious circuit for relay 231. At the same time, a circuit was closed from ground at the left armature and contact of relay 210, left armature and front contact of relay 230, right contacts of key 203, left contacts of key 233, to battery through

the windings of relays 228 and 229 in parallel. Relays 228 and 229 lock to ground at the armature of relay 210, and relay 230 releases. The operation of relay 228 completes the connection of the calling line with the central office trunk and releases relay 222. Relay 229 closes a circuit from battery through the winding of relay 232, right inner armature and front contact of relay 229, left inner armature and front contact of relay 221, left armature and back contact of relay 230, to ground at the left armature of relay 210. Relay 232 locks in a circuit from battery through its winding and locking contact, left normal contacts of relay 217, to ground at the right armature of relay 210. Relay 232 in operating, causes guard lamp 208 to be extinguished as a signal to the attendant that the called subscriber has answered.

When the called subscriber hangs the receiver on the hook, relays 219, 220, 221, 230, 228, 229, 231 and 216 release. Relay 232, however, remains locked. The release of the connector relays 110 and 113 is under control of the central office by means of relay 210, which is operated through the contact of the bridging relay 209. The called subscriber may recall the attendant by operating his switchhook, thus causing the reoperation of relays 219, 220 and 221, and closing a circuit from battery through the right hand winding of relay 218, right outer armature and contact of relay 216, right inner armature and contact of relay 232, left inner armature and back contact of relay 216, right outer armature and contact of relay 223, to ground at the left armature of relay 220, thus causing line lamp 201 to light and signal the attendant. When the central office disconnects, relay 209 releases, in turn releasing relay 210 which causes the release of the remainder of the connection.

45 Calls to the attendant.

For the purpose of talking with the attendant, a local subscriber dials the digit 0, the operation being similar to that described for a local call. In this case, counting relays 1017 and 1019 and transfer relay 1003 will operate, causing the operation of relay 803. Relay 803 locks in series with relay 808 to the grounded conductor 1053 and connects the calling line by means of a primary and an intermediate link with the attendant's line circuit 601. Ringing current is applied to the line 601 in the manner previously described, thus causing relay 604 to operate and the consequent lighting of lamp 602. The attendant answers by operating a key 603 which is associated with lamp 602 and thereby connects her talking set 605 in direct connection with the calling line. Should the attendant restore key 603 while the calling

subscriber is still on the line, relay 609 will operate and light lamp 606 as a holding signal to the attendant.

The attendant is also provided with dialing apparatus and a line circuit 610 by means of which she may communicate with any subscriber, in the manner described for a local call.

Tone circuit.

Whenever relay 801 of an intermediate link circuit or relay 222 of a trunk circuit is operated, relay 551 operates, in turn operating relay 557. Relay 557 in operating, removes the short circuit from the high resistances 553 and 554, thus causing the release of relay 557. This process is continued, resulting in a tone. Relay 551 also closes an operating circuit for slow-release relay 555, relay 555 in turn operating relay 556. Relay 556 in operating, releases relay 555. Each time relay 556 operates, it completes the tone circuit through its right armature and contact to the tone lead 552. From this it will be seen that by means of a cycle of operations of relays 555 and 556, tone current is applied for a certain period and disconnected for another period from the conductor 552.

95 Ringing circuit.

Whenever any link or trunk circuit is in the ringing condition, relay 501 operates, closing an obvious circuit for slow-release relay 503. Relay 503 connects ground through its right armature and contact to operate relay 506. Relay 506 in turn operates relay 507. Relay 507 causes the release of relay 506. By means of the self-interrupting character of relays 506 and 507, ground is intermittently connected at the right armature and back contact of relay 507 to the winding 510 of the ringing transformer.

Relay 503 also connects ground through its left armature and contact, winding of relay 512, right normal contacts of relay 513, to battery. Relay 512 operates and extends this same ground through its left armature and front contact to operate relay 513. Relay 513 after an interval operates and opens the operating circuit of relay 512 which begins to release. While relay 512 is releasing, ground at the left armature of relay 503 is connected through the left armature and contact of relay 513, left armature and back contact of relay 514, left winding of relay 518, to battery through the left winding of relay 514. Relay 518 operates in this circuit, but relay 514 does not. When relay 513 releases, ground is connected through the right inner armature and front contact of relay 518, both windings of relay 518 in series, to battery through the left winding

of relay 514, which now operates. Relay 512 again operates over the previously described circuit, causing the reoperation of relay 513. Relay 513 at its second operation connects ground to the locking contact and left hand winding of relay 514, and shunts the winding of relay 518, which releases. In this condition ground is extended through the right middle armature and contact of relay 518, right outer armature and contact of relay 514, left armature and back contact of relay 515, left winding of relay 519, left winding of relay 515 to battery. When relays 512 and 513 release the second time relay 514 releases, but relay 515 operates in series with relay 519.

The above cycle of operations is repeated, thus causing the reoperation of relay 514 and the release of relay 518. Under this condition relay 515 is locked and relay 519 releases. A similar process brings about the operation successively of relays 516 and 517. It will be observed therefore, that a definite time interval elapses between the successive operation of the several relays 514, 515, 516, etc. It will also be observed that when either relay 514 or 515 is operated battery is connected through the right outer armature and back contacts of relays 521 and 517, right inner armature and back contact of relay 516, right outer armature and back contact of relay 520, right outer armature and front contact of either relay 519 or relay 518 to the middle of winding 510 of the ringing transformer. This battery in conjunction with the vibratory character of relay 507 induces a ringing current in winding 502 of this same transformer. When either relay 516 or 517 is operated this current is disconnected thus providing for definite ringing and silent intervals.

What is claimed is:

1. The combination in a telephone system of a number of telephone lines, connecting relays and link circuits for interconnecting said lines, a set of counting relays for each link circuit and responsive to a series of impulses sent over one of said lines, a second set of counting relays for each link circuit and responsive to a second series of impulses sent over such line, means for switching in the second set of counting relays at the end of the first series of impulses, and circuits selectively closed through contacts of said counting relays to interconnect a calling line with a called line.

2. The combination in a telephone system of a plurality of telephone lines, link circuits, connecting relays having contacts for interconnecting said lines and links, a set of counting relays for each link circuit and responsive to a series of impulses sent over one of the lines, a second set of counting relays for each link circuit and responsive to a second series of impulses sent over such

line, means for rendering the second set of counting relays effective following the first series of impulses, and circuits selectively closed through contacts of said counting relays for operating said connecting relays to interconnect a calling line with a called line through one of said link circuits. 70

3. The combination in a telephone system of a plurality of groups of lines, link circuits, a multi-contact relay for each group of lines for interconnecting said lines and link circuits, a set of counting relays for each link circuit and responsive to a series of impulses sent over one of said lines, a second set of counting relays for each link circuit and responsive to a second series of impulses sent over such line, means effective between said series of impulses for rendering said second set of counting relays effective, and circuits selectively closed through contacts of said counting relays for operating said multi-contact relays to interconnect a calling line with a called line through one of said link circuits. 75 80

4. The combination in a telephone system of a number of groups of lines, link circuits, a multi-contact relay for each group of lines for inter-connecting said lines and links, means responsive to a call on one of said lines for operating a multi-contact relay to connect such line to one of the links, a plurality of sets of counting relays for each link circuit and responsive respectively to successive series of impulses sent over one of said lines, and circuits closed through the contacts of said counting relays for selectively operating another of said multi-contact relays to connect said one of the links to a called line. 90 95 100

5. In combination, a series of counting relays responsive to impulses for controlling circuit connections, means for energizing one of said relays in response to each impulse, means for releasing a previously energized relay in response to the next impulse if such impulse follows immediately, and means for releasing a previously energized relay in response to a second succeeding impulse if the first succeeding impulse does not follow immediately. 105 110 115

6. In combination with a series of counting relays responsive to impulses for controlling circuit connections of means for energizing one of said relays in response to each impulse, means for releasing a particular relay in response to the next impulse, and means to prevent the release of said particular relay in response to a succeeding impulse which follows after an interval provided only one succeeding impulse follows. 120 125

7. In combination with a series of counting relays responsive to impulses for controlling circuit connections of means for energizing one of said relays in response to each impulse, means for releasing a pre- 130

viously energized relay in response to the next impulse if such impulse follows immediately, means for releasing a previously energized relay in response to a second succeeding impulse if the first succeeding impulse does not follow immediately, and means to prevent the release of said previously energized relay in response to a suc-

ceeding impulse which follows after an interval provided no other succeeding impulses follow.¹⁰

In witness whereof, I hereunto subscribe my name this 22 day of December A. D., 1923.

ROBERT W. HARPER.
